UNITED STATES PATENT OFFICE.

ALBION SLAYTON LANG, OF JAMAICA PLAIN, MASSACHUSETTS.

SAXOPHONE CORD.

Application filed December 9, 1925. Serial No. 74,251.

This invention relates to a saxophone cord such as is used by saxophone players to support the weight of the saxophone while it is being played, and it has for its object to 5 provide a novel means for clamping or holding the cord in any adjusted position.

The saxophone cord herein shown is of that type which comprises a length of cord arranged in two loops, one of which is a 10 double loop, and which has a slide at the junction of the loops through which the cord passes a plurality of times whereby the effective length of the cord may be adjusted by adjusting the slide.

15 The object of the present invention is to provide a novel form of slide and a novel lock therefor which will engage the cord and prevent it from slipping after it has been adjusted.

20 In order to give an understanding of my invention I have illustrated in the drawings a selected embodiment of my invention which will now be described after which the novel features will be pointed out in the appended claims.

25 Fig. 1 is a view of a saxophone player playing the saxophone, said figure illustrating my improved supporting cord;

Fig. 2 is a perspective view of the supporting cord;

Fig. 3 is a diagrammatic view illustrating the way in which the cord is formed into the single and double loops;

Fig. 4 is an enlarged perspective view of 35 the locking slide embodying my invention;

Fig. 5 is a section on the line 5—5, Fig. 4;

Fig. 6 is a section on the line 6—6, Fig. 4.

In Fig. 1 of the drawings 1 indicates a 40 saxophone player and 2 a saxophone which he is playing. 3 indicates generally the supporting cord which is looped about the neck of the saxophone player and which is provided at its lower end with a hook 4 adapted to hook into the eye 5 carried by 45 the saxophone.

The support herein shown is of the type in 50 which the cord 3 is formed into an upper loop 6 which encircles the neck of the saxophone player and a double lower loop 7 carrying the hook 4. At the junction of the two loops is a slide indicated generally at 8 which can be adjusted on the cord and by the adjustment of which the effective length of the cord is changed in a well known way. 55 The manner in which the cords are threaded through the slide is illustrated in Fig. 3.

The cord forming one side of the loop 6 is passed through the slide and thence formed into one part or turn of the double loop 7 the cord then being passed through 60 the slide 8 again and formed into the other part or turn of said double loop 7, said cord being then passed through the slide a third time and extending upwardly to form the other side of the upper loop 6, both parts of 65 the double loop 7 passing through the eye 9 of the hook 4. This is a common way of constructing a saxophone cord support and the length of the supporting cord is adjusted by moving the slide 8 up or down thereby to 70 transfer part of the length of the single loop into the double loop or vice versa, all as will be clearly understood by those familiar with 75 saxophone supports of this type.

My present invention relates to a novel 80 form of slide which has cord-gripping means associated therewith. The slide herein shown comprises the two members 10 and 11 which have a telescopic relation. The member 10 is a cup-shaped member open at the 85 end 12 and closed at the end 13, said member having the apertures 14 in two opposed sides through which the strands of the cord 3 pass. The member 11 is constructed to telescope within the member 10, said member also 90 having an aperture 15 through which the strands of the cord pass.

16 is a spring confined between the end of the member 11 and the end 13 of the member 10, said spring tending to force the member 95 11 outwardly and to disalign the apertures 14 and 15. This action of the spring clamps the cord between the side 17 of the aperture 15 and the side 18 of the aperture 14, such clamping action being sufficient to hold the 95 cord from slipping through the slide while the cord is in use.

When it is desired to adjust the length of the cord the operator grasps the slide between the finger and thumb of his hand and 100 presses the ends 13 and 19 toward each other with sufficient pressure to overcome the tension of the spring 16. When this is done the gripping pressure on the strands of the cord will be relieved and the slide may be 105 adjusted up or down to shorten or lengthen the effective length of the cord. When the proper adjustment has been secured the slide is released and the spring 16 will force the member 11 outwardly and thus again grip 110 the cord. This device has the advantage that the release of the grip on the cord is accom-

plished by the motion that the wearer of the cord naturally makes to adjust the slide.

Said adjustment is effected by holding the hook in one hand and grasping the slide with the other hand and then moving the slide up or down. In thus grasping the slide to adjust it a person will naturally take the slide between the thumb and finger and will apply more or less pressure to the slide. The release of the gripping lock, therefore, requires no extra motion and only the application of sufficient pressure on the slide to overcome the tension of the spring 16.

The device has the further advantage that it is simple in construction and inexpensive to manufacture.

I claim—

1. A saxophone support comprising a flexible supporting member constructed to present an upper loop to encircle the neck of the player, and a lower loop, one of said loops being a double loop, a hook supported by the lower loop on which a saxophone is adapted to be hung, a cord-locking slide at the junction of the loops by the adjustment of which the length of the cord is changed, said slide comprising two telescopic members, each having an aperture extending transversely therethrough, the cord passing through both apertures three times, and a spring acting on said members and tending to disalign said apertures and thereby grip the cord.

2. A saxophone support comprising a

flexible supporting member constructed to present an upper loop to encircle the neck of the player, and a lower loop, one of said loops being a double loop, a hook supported by the lower loop on which a saxophone is adapted to be hung, a cord-locking slide at the junction of the loops by the adjustment of which the length of the cord is changed, said slide comprising two members each having an aperture through which the cord passes a plurality of times, said members being slideable with relation to each other, and means to cause a disalignment of said apertures whereby the cord is clamped.

3. A saxophone support comprising a flexible supporting member constructed to present an upper loop to encircle the neck of the player, and a lower loop, one of said loops being a double loop, a hook supported by the lower loop on which a saxophone is adapted to be hung, a cord-locking slide at the junction of the loops by the adjustment of which the length of the cord is changed, said slide comprising a cup-shaped member having apertures in opposed sides, a second member telescoping within the cup-shaped member and also having an aperture, the cord passing through both apertures a plurality of times, and a spring acting on said members tending to disalign the apertures.

In testimony whereof, I have signed my name to this specification.

ALBION SLAYTON LANG.
